LAMP BASE

Harold B. Hackney and Ben Harkins, Chicago, Ill., assignors to Automatic Tripod, Inc., a corporation of Illinois

Filed Feb. 26, 1963, Ser. No. 73,723

Term of patent 14 years

(Cl. D48—20)

The dominant features of the design are shown in solid lines.

We claim:

The ornamental design for a lamp base, as shown and described.
